United States Patent Office

Des. 179,683
Patented Feb. 12, 1957

179,683

SOAP HOLDER

Reginald A. Harrison, De Queen, Ark.

Application April 26, 1956, Serial No. 41,210

Term of patent 7 years

(Cl. D4—3)

The broken line portion in Figure 1 is shown for illustrative purposes only.

I claim:

The ornamental design for a soap holder, as shown and described.
